DOLL.

Application filed February 9, 1921. Serial No. 443,599.

To all whom it may concern:

Be it known that we, JOHN A. STREET and EDWARD F. WANTLAND, citizens of the United States, and residents of Los Angeles, in the county of Los Angeles and State of California, have invented new and useful Improvements in a Doll, of which the following is a specification.

This invention relates to a doll or manikin having novel means to hold a picture or like object.

It is the primary object of this invention to provide a doll having at the heart spot means to mount a picture, miniature, or keepsake, whereby an ornamental article may be provided which appeals to the sentiments.

These objects together with other objects and corresponding accomplishments are obtained by means of the embodiment of our invention illustrated in the accompanying drawing, in which:

Fig. 1 is a face view of a doll embodying our invention; and Fig. 2 is an enlarged fragmentary section as seen on the line 2—2 of Fig. 1.

Referring more particularly to the drawing, 3 indicates a doll. This doll may be constructed from any one of the well known materials used in the manufacture of such articles, the particular form of the doll or the expression of the face is not material to the invention. The doll may be a male or female depending upon the nature of the picture to be mounted thereon and the sex of the possessor. However, on or in the chest of the doll at the heart spot means is provided for mounting a picture, this being an essential part of the invention.

As shown herein, a case 4 is embedded in the body and is provided with a hinged cover 5. The case and cover are in the nature of a locket suitable for mounting a picture 6 therein. The case and cover are preferably of heart shape to further emphasize the sentimental appeal. If desired, the cover and case may be arranged so that the cover can be locked in its closed position.

The use of the doll is obvious. For illustration, a young lady may have a female doll and mounted in the case a picture of her sweetheart.

We do not limit ourselves to the specific form of the mounting for the picture or the shape of the mounting. It may be found preferable in some instances to have no independent cover on the doll for concealing the picture. In such cases the usual doll clothing may serve that purpose.

What we claim is:

1. An article of manufacture comprising a doll's body having at the heart spot a heart shaped mounting for a picture.
2. An article of manufacture comprising a doll's body having at the heart spot a heart shaped casing provided with a cover for mounting a picture therein.

In witness that we claim the foregoing we have hereunto subscribed our names this 3rd day of February, 1921.

JOHN A. STREET,
EDWARD F. WANTLAND.
